UNITED STATES PATENT OFFICE.

ROBERT A. KELLER, OF CATASAUQUA, AND CLINTON F. ROTH, OF ALLENTOWN,
PENNSYLVANIA.

HORSESHOE-CALK.

1,187,332.

Specification of Letters Patent. Patented June 13, 1916.

Application filed March 5, 1915. Serial No. 12,322.

To all whom it may concern:

Be it known that we, ROBERT A. KELLER and CLINTON F. ROTH, citizens of the United States, residing at Catasauqua, in the county 5 of Lehigh and State of Pennsylvania, and Allentown, county of Lehigh, and State of Pennsylvania, respectively, have invented new and useful Improvements in Horseshoe-Calks, of which the following is a specification.

The present invention contemplates the provision of calks carried by an attaching plate capable of being readily attached to or removed from the shoe of the animal 15 when desired, especially during sleety weather, the calks being designed to prevent the animal from slipping.

Among other features the invention embodies simplicity in construction, cheapness 20 in manufacture, durability and efficiency in use.

The invention is fully set forth in detail in the following description, shown in the drawing wherein like numerals of reference 25 indicate similar parts in the several views and in which:—

Figure 1 is a bottom plan view of the shoe with the calks associated therewith. Fig. 2 is a longitudinal sectional view taken on line *a—a* of Fig. 1. Fig. 3 is a sectional view taken on line *b—b* of Fig. 1. Fig. 4 is a detail view of the toe calk and attaching plate.

Upon reference to the drawing in detail 35 5 designates the body of the horse shoe, the latter being of usual construction.

The toe and heel calks 6 and 7 respectively, forming the subject matter of our invention, may be constructed from any 40 suitable material preferably forged steel. The former consists of an attaching plate 8 of substantially rectangular formation in cross section, curved longitudinally to conform to the curvature of the shoe, and provided with projections 9 extending from each of the four corners thereof, which are bent upwardly into engagement with the inner and outer edges of the shoe, subsequent to the proper positioning of the plate 45 thereon. The undersurface of the plate 8 is tapered inwardly to coöperate with the oppositely tapered upper surface of the shoe to prevent relative movement between

these parts when in use, the plate being additionally secured to the shoe by means of 55 the fastening element 10. Projecting centrally from the inner edge of the plate 8 is a tongue 11 adapted to be bent upwardly into a correspondingly shaped recess 12 in the inner edge of the shoe, to further assist 60 in obviating turning or twisting of the plate thereon, and to relieve the fastening element 10 and projections 9 of undue strain. The calk proper indicated at 13 is substantially 65 half-moon shaped, and coextensive in length with the plate 8, whereby the calk obtains an effective purchase upon the surface and prevents slipping of the animal. By reason of the specific formation of the calk 13, the latter will wear in such manner so as to 70 always retain a sharp edge.

Both of the heel calks are similarly constructed, and consist of a plate 14 of greater width than the width of the heel, the projecting portions 15 being adapted to be bent 75 into engagement with the opposite edges of the shoe, to retain the same thereon, the plates being additionally secured to the shoe by means of the fastening element 16. One of the projecting portions 15 is arranged in 80 a correspondingly shaped recess 17 formed in the inner edge of the shoe to prevent turning or twisting of the plate thereon. The heel calk proper indicated at 18 is substantially L-shaped, to obtain an effective 85 purchase with the surface, to prevent slipping of the animal, and possesses the same advantages with respect to its wear as that described in connection with the toe calk. Manifestly by reason of the construction 90 hereinabove described either the toe or heel calks, or both may be readily associated with or detached from the shoe when desired, and when associated therewith will be held fixed relatively to the shoe.

It is believed that from the foregoing description the nature and advantages of the invention will be readily apparent without requiring a more extended explanation and therefore the same has been omitted.

What is claimed is:—

As a new article of manufacture, a horse shoe calk comprising an elongated plate of a width greater than that of the shoe, means for fastening said plate to one side of the 105 shoe, whereby said projecting portions of

the plate are adapted to be set up into engagement with the opposite edges of the shoe, and a substantially L-shaped strip of uniform thickness projecting from the outer side of said plate and having its respective branches disposed in parallelism with two of the adjacent edges of said plate.

Copies of this patent may be obtained for five cents each, by addressing the "Commissioner of Patents, Washington, D. C."

In testimony whereof we affix our signatures in presence of two witnesses.

ROBERT A. KELLER.
CLINTON F. ROTH.
